(57) **CLAIM**

The ornamental design for a front side cowl for motorcycle, as shown and described.

DESCRIPTION

FIG. 1 is a perspective view from a front side of a front side cowl for motorcycle;

FIG. 2 is a perspective view from a rear side thereof;

FIG. 3 is a perspective view from a front side thereof;

FIG. 4 is a perspective view from a rear side thereof;

FIG. 5 is a front elevation view thereof;

FIG. 6 is a right side elevation view thereof;

FIG. 7 is a left side elevation view thereof;

FIG. 8 is a top plan view thereof;

FIG. 9 is a bottom plan view thereof; and,

FIG. 10 is a reference view showing use thereof.

The broken lines shown illustrate portions of the front side cowl for motorcycle that form no part of the claimed design. The rear elevation view of the front side cowl for motorcycle is omitted because this view is not visible when the article is in use.
